(57) **CLAIM**

The ornamental design for a cap as shown and described.

DESCRIPTION

FIG. 1 is a perspective view of a cap according to the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a reference view showing use of the cap with a hot/cold compress.

The dot-dash broken lines in FIG. 7 illustrate the bounds of the claim. The dash-dash broken lines showing a hot/cold compress in FIG. 8 illustrate environmental structure. The remaining dash-dash broken lines illustrate portions of the cap. The broken lines form no part of the claimed design.

1 Claim, 6 Drawing Sheets
